VALVE MECHANISM

Ernest J. Svenson, Rockford, Ill., assignor, by
mesne assignments, to Odin Corporation, Chi-
cago, Ill., a corporation of Illinois

Original application March 30, 1936, Serial No.
71,754, now Patent No. 2,266,829, dated Decem-
ber 23, 1941. Divided and this application Jan-
uary 22, 1941, Serial No. 375,501

21 Claims. (Cl. 60—97)

This invention relates to control mechanisms, and more particularly to control valves or the like adapted for the control of hydraulic circuits and hydraulic structures.

It is an object of the invention to provide a control valve structure of improved construction and improved operating characteristics.

More specifically stated, it is a primary object of the invention to provide a control valve structure incorporating hydraulic control elements and electric control elements cooperable in a novel and improved manner, the hydraulic control elements controlling the functions of the electrical control elements, and the electrical control elements in turn controlling the functions of the hydraulic controls.

A further object of the invention is to provide a control valve structure, operable mechanically, hydraulically and electrically, for controlling the various functions of a hydraulic circuit, and machine parts operated thereby, including the functions of rapid and feeding movements in both forward and reverse directions, as may be required.

Another object of the invention is to provide a valve structure having hydraulically and electrically operable control elements arranged for cooperation in accurate and predetermined timed sequence whereby to effect accurate and reliable control functions.

Still another object of the invention is to provide a control valve structure including a plurality of valve members, each controlling the operation of the other.

Various other objects, advantages, and features of the invention will be apparent from the following specification when taken in connection with the accompanying drawings wherein certain preferred embodiments of the invention are set forth for purposes of illustration.

In the drawings, wherein like reference numerals refer to like parts throughout:

Fig. 1 is a partial, elevational view of a machine tool including a valve structure constructed in accordance with the principles of the invention;

Fig. 2 is a diagrammatic view of the hydraulic circuit for the machine of Fig. 1, and including the valve structure of the invention;

Fig. 3 is an enlarged, elevational view of the valve structure;

Fig. 4 is a transverse, sectional view of the valve taken substantially along the line 4—4 of Fig. 3, the control handle and dogs for the valve being detached from the vertical valve shaft;

Fig. 5 is an enlarged, fragmentary, sectional view of the valve taken substantially along the line 5—5 of Fig. 3;

Fig. 6 is a vertical, sectional view of the valve mechanism taken substantially along the line 6—6 of Fig. 4;

Fig. 7 is a fragmentary, transverse, sectional view taken substantially along the line 7—7 of Fig. 6;

Fig. 8 is an enlarged, fragmentary view (shown partly in section) of the contactor mechanism mounted within the control valve housing;

Fig. 9 is an enlarged, fragmentary, elevational view of the valve structure and juxtaposed parts in association with its operating dogs;

Fig. 10 is a fragmentary, plan view of the control dog structures;

Fig. 11 is a detailed, elevational view of a two-direction magnetic actuator associated with the valve, and shown in Fig. 9;

Fig. 12 is a fragmentary, transverse, sectional view taken along the line 12—12 of Fig. 11;

Fig. 13 is a central, longitudinal, sectional view of a modified magnetic actuator;

Fig. 14 is an elevational view of a machine tool, including a plurality of head frame structures as shown in Fig. 1, and each including valve mechanism constructed in accordance with the invention, the electrical control arrangement for the machine also being partially disclosed;

Fig. 15 is an enlarged, elevational view of the electric control panel;

Fig. 16 is an elevational view of a limit switch associated with each head frame structure, as illustrated in Fig. 14;

Fig. 17 is a transverse, sectional view taken substantially along the line 17—17 of Fig. 16;

Fig. 18 discloses an electric circuit diagram of the machine including the circuits in association with the control valves of the invention;

Fig. 19 is a central, vertical, sectional view of a modified control valve mechanism designed to control the feeding of a machine part or the like in opposite directions, said view being taken substantially along the line 19—19 of Fig. 20;

Fig. 20 is an enlarged, transverse, sectional view of the modified control valve mechanism taken substantially along the line 20—20 of Fig. 19;

Fig. 21 is a horizontal, sectional view of the modified valve mechanism taken substantially along the line 21—21 of Fig. 19.

This application is a division of my copending application, Serial No. 71,754, filed March 30, 1936, and entitled Metal working apparatus, now

issued as Patent No. 2,266,829, dated December 23, 1941. The present application is directed more particularly to the control valve structure and while, for purposes of explanation and illustration, the control valve is set forth and described in association with a particular machine tool arrangement for which it has been adapted, it is to be understood that the control valve structure may be adapted for various uses generally, including the control of machine tools, within the scope of the invention defined.

Referring more particularly to the drawings, and first to Figs. 1, 2 and 14 thereof, Fig. 14 discloses a machine tool structure including a plurality of head frame units 40a, 40b and 40c, one 10 of which is illustrated more in detail in Figs. 1 and 2, and designated by the numeral 40. The head 40, Fig. 1, is slidably mounted on the main machine base or frame 42 by means of ways 48, and is adapted to carry a plurality of rotatable tool spindles 112. A fluid motor indicated generally by the reference numeral 114, Figs. 1 and 2, and comprising a piston 118 and piston rod 120 secured to the main base 42 and a cylinder 116 carried by the head frame unit 40 is provided for propelling the head frame along the ways 48. Pumping means comprising a rapid traverse pump 134 and a feed pump 136, Fig. 2, are provided in cooperation with control valve means 208, which valve means more particularly constitutes the subject matter of the present invention, for supplying and controlling the delivery of fluid to the hydraulic motor 114.

Each head frame 40 carries a suitable prime mover such as an electric motor 50, Fig. 1, which drives the tool spindles 112 and the pumps. To this end the electric motor 50 carries a pulley 64 adapted, by means of belts 66, to drive a pulley 62 carried by a main drive shaft 54. This drive shaft drives the spindles 112 by suitable driving connections, and is also provided with a gear 98 adapted to drive a shaft 140 which in suitable manner is connected to and propels the rapid traverse pump 134 and the feed pump 136, preferably one pump being mounted at either end of the shaft and operated thereby.

The rapid traverse pump 134 is preferably a gear pump and may, for example, be of the design disclosed in my Patents Nos. 1,912,737 and 1,912,738. The feed pump 136 is preferably an adjustable, variable displacement plunger pump. The details of construction of the feed pump, and the particular manner in which the pumps are driven and connected with the fluid supply reservoir and the like are specifically set forth in my aforementioned application, Serial No. 71,754 of which this application is a division, and it is not believed necessary to herein particularly set forth these details of construction. However, the fluid circuits as associated with the valve structure 208, are diagrammatically indicated in Fig. 2 and will be later described.

Valve structure

Referring to the control valve structure 208, Figs. 1, 2 and 3-8, one control valve being provided for and carried by each head structure, this valve structure is somewhat similar to the corresponding valve mechanism disclosed in my co-pending applications, Serial No. 481,742, filed September 13, 1930, now issued as Patent No. 2,078,696, dated April 27, 1937; and Serial No. 627,025, filed July 30, 1932, now issued as Patent No. 2,363,707, dated November 28, 1944.

The valve mechanism of the present applica-

tion differs materially from my other valve structures in providing a single control arrangement for the hydraulic and electrical structures of each head frame. It has heretofore been the practice in using control valves to limit said valves to the control of hydraulic circuits and to employ other control means for the electrical circuits. My invention contemplates a valve arrangement whereby the shifting of a single control handle serves to govern both the hydraulic and electrical circuits. To accomplish this I have incorporated directly within the valve housing an electrical contactor, about to be described, which functions in response to the shifting of the main control valve.

Each control valve 208 comprises two shiftable valve members or valve pistons 212 and 214, Fig. 6, which cooperate in variously directing fluid to the actuator 114 from the rapid traverse pump 134 and the feed pump 136 as may be best understood by reference to Fig. 2. The valve piston 212 controls the fluid from the rapid traverse pump, and the valve piston 214 controls the fluid from the feed pump. Valve piston 212 is shifted by means of an operating shaft 252, Fig. 4, operated by control mechanism later to be described. The valve piston 214 is shifted hydraulically by means of and in accordance with the movements of the valve piston 212. The valve piston 212 has essentially four operating positions, neutral, feeding, rapid approach or rapid traverse in the approach direction, and rapid reverse or rapid traverse in the reverse direction. The valve piston 214 has two positions of operation, neutral or circulating position, and feed position. When the valve 212 is in neutral position, the port 236 thereof is aligned with a passageway or port 282. When the valve is in feeding position, port 234 is aligned with passageway or port 278. When the valve is in rapid approach position, the port 234 is aligned with the valve port 230, and when the valve is in rapid reverse position, the port 236 thereof is aligned with port 226. The function of these several ports will be later described. The feed pump valve 214 is shown in its feed position in Fig. 6 wherein the port 262 is blocked by the valve head 215. When the valve is shifted to the right it is in its neutral or circulating position and in this position the port 266 is closed by the valve head 217.

Referring further to Fig. 6, it will be seen that a port 216 communicating with the valve piston 212 receives fluid from the rapid traverse pump 134, by means of a conduit 388, Fig. 2, and when the valve piston is in its neutral or feeding positions, this fluid is allowed to circulate through the port 218 and a restricted orifice arrangement 220 into the exhaust valve chambers 222 and 224 which discharge into a suitable fluid reservoir carried by the head frame 40. Accordingly with the valve in neutral or feeding position, fluid from the rapid traverse pump is inoperative to shift the actuator 114.

As will be best understood by reference to Fig. 7, the valve ports 234 and 236 are in constant communication with the inlet port 216 by means of flats or channels 242 and 244 formed on the body of the valve 212. To effect rapid approach of the fluid motor 114, the valve 212 is shifted, as previously stated, so as to align the port 234 thereof with the port 230 formed in the valve body 254. The port 230 is in constant communication with a channel or conduit 232, Fig. 2, leading to one end of the actuator 114. Accordingly

when the valve 212 is in this position, fluid will be transmitted from the rapid traverse pump to the actuator 114 to effect the shifting thereof. Fluid is returned from the other end of the actuator through a channel or conduit 228 which is connected to the port 226, the port 226 being free to communicate with the exhaust chamber 224 in this position of the valve, inasmuch as the end of the valve has been moved to the right of the port 226 as seen in Fig. 6.

To effect rapid reverse, or rapid traverse of the actuator in the opposite direction, the valve 212 is shifted, as previously stated, to align the port 236 thereof with the port 226 in the valve housing 254. In this position of the parts fluid is directed by the valve 212 from the rapid traverse pump through ports 236 and 226 and conduit 228 to one end of the actuator 114. The return fluid from the actuator is transmitted through conduit 232 into port 230, and then into the exhaust valve chamber 222, the port 230 being in free communication with chamber 222 when the valve has been shifted to the left as seen in Fig. 6, to align the ports 236 and 226. End caps 238 and 240 serve as retainers or closures for the exhaust chambers 222 and 224 and also as stops for the valve member 212 in its movement in both directions.

The valve structure is so arranged that substantially no fluid pressure exists within the chambers 222 and 224, inasmuch as these chambers communicate directly with the reservoir, but suitable low pressure exists within the valve ports 216, 234 and 236 even when the valve 212 is in neutral or feeding position, due to the orifice arrangement 220. In order to vary the size of the orifice when the displacement of the rapid traverse pump is increased or decreased, for example to conform the orifice to the particular size of pump being used, a nozzle arrangement 246 is provided, said nozzle being threaded into the valve member 212 as indicated at 248. The nozzle 246 is provided with a passageway 250, Figs. 6 and 7. When the nozzle is in the position shown, the passageway 250 is relatively unrestricted. By rotating the nozzle 246, the passageway 250 may be moved toward a horizontal position whereby to restrict it any desired amount.

As previously stated, the valve member 212 is shifted either manually or automatically by the shaft 252, Fig. 4. This shaft is rotatably mounted within the valve housing 254, suitable packing 256 being provided to preclude leakage. A lever 258 connects the shaft 252 with the valve member or piston 212 through the agency of a pin 260 so that the rotation of the shaft 252 in one direction or the other, by means later to be described, causes movement of the valve piston 212.

Referring now to the valve piston 214 which serves to control fluid from the high pressure or feed pump 136, it will be seen that a pair of ports 262 and 266 in alignment with ports 230 and 226 respectively are provided. Port 262 communicates with port 230 and its associated and connected conduit 232 by means of a channel 264, and port 266 communicates with the port 226 and its connected conduit 228 by means of a channel 268. As best seen in Fig. 2, the conduit 232 is connected to the exhaust conduit 388 leading from the feed pump, and an inlet or return conduit 390 leads from the valve 214 back to the inlet side of the pump.

When the valve piston 214 is in its feeding position, as shown in Fig. 6, high pressure fluid will be directed from the feed pump 136 through the

conduit 388 and the lower end 232a, Fig. 2, of the conduit 232 to the actuator 114. Fluid is prevented from passing upwardly through conduit 232 into the valve 208 due to the fact that the head member 215 on the valve 214 at this time blocks the port 262, and the port 230 is also blocked by the valve 212, the valve 212 being at this time in its feeding position. An approach feeding movement of the actuator is thus effected. Fluid is returned from the actuator through the conduit 228, port 266 which is at this time open and the return line 390 back to the pump, the port 266 and the return line 390 being at this time in communication as seen in Fig. 6.

When the valve member 214 is shifted to the right as seen in Fig. 6 to its neutral or circulating position, the piston head 215 shifts to the right opening port 262, and piston head 217 shifts to the right closing port 266. Under these conditions fluid circulates from the feed pump through conduit 388, the upper portion of conduit 232, port 262 and return line 390 back to said pump, the port 262 and the line 390 at this time being in communication. With the valve 214 in neutral position therefore the fluid from the feed pump is merely circulated idly in a closed circuit. It is to be understood that fluid passes from the port 262 or the port 266 to the return line 390 along the body of the valve member 214 under the conditions of operation above described.

To preclude leakage, there are no exterior operating connections to the valve piston 214, such being rendered unnecessary because the valve piston 212 functions to control the shifting of the valve 214 in one direction or the other hydraulically by directing fluid pressure either to one end or the other of the valve piston 214, by means now to be described. To more clearly illustrate this arrangement, I have shown in dotted lines in Fig. 6, see also Fig. 3, a longitudinal channel 270 at the right of the valve casing 254, and the corresponding channel 272 at the left of said valve casing. Cross channels 274 and 276 connect with said longitudinal channel 270 and the bore of the casing within which the valve 214 is movable, and additional cross channels 278 and 280 connect the longitudinal channel 270 with the bore of the casing in which the valve 212 is movable. In a similar manner cross channels 282 and 284 connect the longitudinal channel 272 with the casing bore for the valve 212, and the cross channel 285 serves to connect the channel 272 with the left extremity of the bore within which valve 214 is movable.

When the valve piston 212 occupies its feeding position, port 234 will be aligned with channel 278 causing the introduction of pressure fluid to the right end of the valve piston 214 through channels 278, 270, 274 and 276, thereby causing the shifting of the same to the left into its feeding position. Upon the shifting of the valve, fluid at the opposite or left end thereof is returned through channels 285, 272 and 284 into the exhaust chamber 224, the channel 284 being at this time in free communication with said chamber. Similarly when the valve piston 212 is shifted to its rapid approach position, aligning port 234 with port 230, fluid pressure is also transmitted to the channel 278, due to the flats or channels 242 and 244, Fig. 7, previously referred to. It will thus be seen that the valve 214 is shifted to its feed position when the valve 212 is shifted either to its feed or rapid approach positions.

When the valve member 212 is shifted to its neutral position, to align the port 236 with the channel 282, fluid is directed through channels

282, 272 and 285 to the left end of valve piston 214, causing the shifting of the same to its right or neutral circulating position. During the shifting of the valve 214, fluid passes from the chamber at the right end thereof through the channels 274 and 276, as will be later described, channel 270, and channel 280 which is at this time in free communication with the exhaust chamber 222. Similarly upon the shifting of the valve 212 to its rapid reverse position, wherein port 236 is aligned with port 226, due to the ports 242 and 244, Fig. 7, fluid will similarly be directed through the channels as described to move the valve 214 to the right. Accordingly it will be seen that the valve 214 is shifted to its neutral position when the valve 212 is shifted to its neutral or rapid reverse positions.

An electrical contactor 286 is secured to the valve housing 254 by means of a threaded coupling 288 and suitable gaskets at 290 and 292. A plunger 294 is reciprocably mounted within the contactor body 296 and abuts against a sealing diaphragm 298, which is normally urged to the left, Figs. 6 and 8, by a spring 300. When the valve piston 214 engages the plunger 294 as it is shifted to the right, the latter is urged outwardly against the spring 300, causing a contact 302, Fig. 8, to close a connection between a contact 304 and another contact 306, thereby electrically connecting a wire terminal 308 in a circuit with a companion wire terminal 310. The closing of this circuit forms part of the control means for shifting valve 212, and more specifically causes the shifting thereof to its rapid reverse position, as will be later described.

By loosening screw 312, the wire terminals 308 and 310 may be rotated about the axis of the plunger 294 to any desired position. To prevent fluid pressure from acting upon the diaphragm 298, a channel 314 in the valve body 254 leading to chamber 222 is employed. Further, a spring 316 serves to resiliently retain contact 302 in proper contact with the contact members 304 and 306.

In many instances it is desirable to have a slight dwell of an actuated member such as the head frame 40 before reversal thereof takes place. This is accomplished by restricting the channel 274, as shown in Fig. 5, whereby to delay the shifting of valve 214 to the right to close contacts 304 and 306 and move valve 212 to its rapid reverse position. A needle valve 318 is adjustably positioned to increase or decrease the speed of fluid passing through the cross channel 274. Therefore, when the valve piston 214 is actuated to the right, it experiences rapid movement until a forward portion 320 of said piston blocks the unrestricted cross channel 276. This causes the speed of travel of the piston to be materially reduced as restricted channel 274 becomes the only channel of fluid escape until a groove 322 connects with the cross channel 276, which through two longitudinal channels 324 again permits fluid to pass through unrestricted channel 276. This enables a sudden snap action to take place as the valve member 214 shifts the piston 294 of the electrical actuator 286. In other words, it causes a snap action to be experienced by the contact 302 when it makes contact with the contact members 304 and 306.

Likewise, when the valve piston 214 is shifted in the opposite direction, the restriction through the cross channel 274 provides a dash pot action, and thus eliminates hammering action which

might otherwise take place between the valve member 214 and an end cap 326.

As previously brought out, the fluid to and from the feed pump 136 circulates in a closed circuit, both when the pump is operatively propelling the actuator 114 at feeding speed and when the pump is merely circulating idly due to the neutral positioning of the valve 214. However, due to the presence of piston rod 120 on one side of the actuator piston 118 and the absence of the piston rod on the other side thereof, or due to other features, a difference may exist in the volumetric requirements on the inlet and outlet sides of the actuator during its feeding movement. These differences, and leakage which might occur, are compensated for by an orifice 328, Fig. 6, which leads from the port 236 into the bore of the valve casing within which the valve 214 is movable. This orifice which thus leads from the exhaust side of the rapid traverse pump into the closed circuit for the feed pump, automatically functions to maintain proper pressure conditions within the inlet side of the feed pump.

From the above description it will be apparent that the valve mechanism 208 is capable of directing one source of fluid to the actuator in one direction or another, and another source of fluid to the actuator at least in one direction; further, that the fluid flow from one of the pumps is controlled in response to the fluid flow from the other pump, and that an electrical contactor is incorporated in the valve structure and is adapted to make a snap contact in response to fluid power from one of the pumps. It will also be apparent that said valve structure incorporates a dwell arrangement whereby both pumps may circulate at no pressure, thereby stopping the actuator at a predetermined time before contact is established by the electrical contactor. The function of the contactor 286 will be more apparent when the electrical and remote control arrangement is described.

Valve control

As previously stated, and referring to Fig. 14, three machine tool units 40a, 40b and 40c are provided, each having and carrying its own pumps, actuator and control valve mechanisms.

These units must be shifted toward and away from a work supporting fixture or the like 392, as indicated by dot and dash lines in Fig. 14, in proper timed relation. This is accomplished by the action of the control valves and their associated controlling devices now to be described.

It is to be noted that the electrical contactor 286 for each control valve is secured to the valve housing 254, and that the valve housing is in turn secured directly to its associated head frame structure. A stationary control bar 394, Figs. 9 and 10, for each head frame unit is secured to the machine base 42 in any suitable manner, and this bar serves as a support for a plurality of control dogs. A control dog 396 serves to operate an electrical contactor 398, Figs. 9, 10, 16 and 17, said control dog 396 being provided with specially shaped contact faces 400 adapted to engage a roller 402. The engagement of roller 402 shifts various contacts housed within the contactor in a manner presently to be described.

An upper control cam 404 and a lower control cam 406 secured to the shaft 252, see Fig. 3, serve to shift the valve piston 212 in one direction or the other when engaged by control dogs 75 408, 410 and 412. In Fig. 10 the shaft 252 and

its associated cams are shown in three different operative positions which they assume in the movement of the head frame. The shaft is shown at 252 in the position which it assumes when the head frame is in restored or home position. It is shown at 252a in its position at the beginning of the feeding movement of the head, after its rapid approach, and at 252b in the position assumed at the end of the feeding operation, at which time the head begins its rapid reverse movement. The control dog 412 engages the upper control cam 404 through the agency of a positive abutment member 414, and a resilient abutment member 416. The abutment member 416 is adjustable by means of a suitable nut 418 and spring 420 and serves to actuate the control cam 404 through a greater distance than that imparted by the abutment member 414. This arrangement insures the complete shifting of the valve 212 to neutral as the head frame is restored to home position. By means of the various control dogs 408, 410, 414 and 416, the valve control shaft 252 is shifted to its various operating positions during the cycle of movement of the head frame, as will be later described.

To enable the remote control of the heads 40a, 40b and 40c, as shown in Fig. 14, I prefer to employ a two-direction magnetic actuator 422, Figs. 9 and 11, one for each head, which consists of a power transmitting member 424 having a positive stop 426 at one extremity and a positive stop 428 at the opposite extremity whereby to decrease current requirements and to eliminate the possibility of hammering action which might otherwise be experienced. Actuator 422 is operatively connected by a crank 438 to valve shaft 252 as shown in Fig. 12. A manual control handle 436 is also connected to the assembly. A magnetic coil 430 shifts the power transmitting member 424 in one direction to shift valve 212 for effecting the forward travel of the head frame, and a similar coil 432 shifts the member 424 in the opposite direction to shift valve 212 to effect reverse movement of the head frame. A suitable bracket 434 serves as a support for the magnetic actuator 422. This arrangement enables free movement of the power transmitting member 424 and positively precludes any binding or the like. I have found that if the power transmitting member 424 is positively connected to another member, such as the manual control handle 436, a binding of the member 424 is likely to occur. Therefore I have provided a loose or free connection between the power transmitting member 424 and said control handle 436. By mounting the power transmitting member 424 in the manner described I am able to obtain the benefit of the vibratory action to which said member is subjected by the action of the magnetic coils 430 and 432. Such vibratory action materially decreases the power which is required to shift the member 424. In fact, I have found that by mounting the member 424 as described it requires only three to four pounds pressure to shift the valve piston 212 through the slotted crank member 438, the shaft 252, and the associated connecting elements. On the other hand, if the magnetic actuator is rendered ineffective and a force exerted against the crank arm 438, a considerable increase in starting power is required to shift the valve piston 212. I have found that the friction which resists the initial actuation of the valve requires up to two and one-half times the amount of power avail-

able in the magnetic actuator. From the foregoing it will be apparent that the use of the power transmitting member 424 in combination with the magnetic coils 430 and 432 provides a very efficient means for shifting the valve piston 212.

I have thus far described the hydraulic control and have made reference to certain of the electrical control devices associated therewith. I shall now describe in more detail the electrical circuit arrangement which cooperates with the hydraulic circuit arrangement and control valves in controlling the timed functioning of the slideable heads.

Referring to Figs. 14 and 15, it will be observed that I provide a main control panel, designated generally by the numeral 440, which may be secured in a position most convenient to the operator. In Fig. 14, wherein I have shown a plurality of self-contained actuator units, the control panel is conveniently mounted on the base 42 directly beneath the left head 40a. This single control panel controls all three heads. I have shown electric power lines L-1, L-2 and L-3 connected through suitable magnetic controllers 442 to the prime movers of each head, only one magnetic controller being shown and said prime movers being indicated diagrammatically and designated as numbers 1, 2 and 3. A number of push buttons 444, 446 and 448 are employed, each of said buttons being companion to one of the prime movers. For purposes of clearness the buttons 444 in Fig. 15 are designated by No. 1, the buttons 446 by No. 2, and the buttons 448 by No. 3, to indicate the prime movers or motors which these buttons control. The arrangement is such that the upper button in each instance initiates operation of its associated motor, and the lower button stops the operation thereof. This action is effected by closing and opening the corresponding magnetic controllers 442 by suitable button operated magnets, and inasmuch as such controls are conventional, the specific electrical control circuit for these operations has not been illustrated.

It will be seen that two heavy-duty push buttons 451 and 463 marked "Start" and "Reverse" are incorporated for the purpose of hydraulically shifting the individual machine tool units or any number of units as a group, the shifting of each unit being dependent on whether the prime mover for such unit is in operation. More specifically if the push button 444 is manipulated to close the magnetic controller 442 and thereby energize No. 1, the "Start" and "Reverse" push buttons will then remotely control the machine tool unit or head 40a. Likewise by manipulating either the buttons 446 or 448 the heads 40b and 40c, respectively, may be remotely controlled through the agency of the "Start" and "Reverse" buttons. If all of the groups of buttons 444, 446 and 448 are manipulated for energizing their respective motors, all of the heads 40a, 40b and 40c may be controlled in unison by the "Start" and "Reverse" buttons. It is well known that many cutting tools cannot withstand the stopping of the prime mover without causing the cutting edge to break. Therefore I aim to so construct the control arrangement that the operator may, if some unforeseen emergency arises, merely reverse all of the heads together and thereby preserve the cutting tools. It is for this purpose that the "Reverse" button is provided, as will later be described.

In Fig. 18 I have diagrammatically illustrated

the preferred wiring arrangement to be used for the remote control just referred to. It will be seen that the main power lines L-1, L-2 and L-3 are selectively connected to the various motors No. 1, No. 2 and No. 3 through the magnetic controllers 442 adapted to be operated by the push buttons 444, 446 and 448 as previously described. These controllers, and their usual associated holding circuits, are of commercial design and well known to those skilled in the art and hence need no further description.

The control circuit illustrated in Fig. 18 for controlling the hydraulic shifting of the several head frame structures will now be described. As previously stated, the magnetic coil 430 of each magnetic actuator 422 is adapted to actuate its associated valve piston 212 to rapid approach position whereas the companion coil 432 of the magnetic actuator is adapted to operate the valve to rapid reverse position. As also previously stated, the remote control of all the valves is adapted to be effected from the single control "Start" and "Reverse" buttons 451 and 463. To this end the button 451 when operated energizes a coil 452, Fig. 18, the button operating to close the circuit through the coil from the line L-3 to the line L-1 by means of a main switch 456 which must first be closed to condition the electrical control circuits. Coil 452 when energized closes a set of contacts 454 which, when closed, establish a holding circuit for coil 452 from line L-3 through the coil 452, the contacts 454, auxiliary contacts 450, respectively associated with and closed by the contactors 442, contacts 460 which are now closed, and the magnetic controllers 442 back to the line L-1. It will be noted that if none of the motors has been energized by the push buttons 444, 446 and 448, then none of the contacts 450 will be closed and the holding circuit 452 is not established. The energization of any motor, however, will establish the holding circuit. The operation of coil 452 also closes switch contacts 457, one for each head structure, and these contacts individually energize their associated coils 430 by closing the circuit from the line L-3 through the magnetic contactors 442 through the contacts 457, the contacts 458 which are now closed, the coils 430, and the contactors 442 back to the line L-1. It will be seen that the coil 430 for each head structure for shifting valve 212 to rapid approach position is energized only if the magnetic controller 442 for such head is closed.

As each head structure moves from home position, dog 396 is disengaged from roller 402 and operates its associated limit switch 398 whereby to open switches 458 and 460 and close switch 462 (see Figs. 16 and 18). The opening of these switches breaks the holding circuit for the coil 452 and also deenergizes the forward actuating coils 430. The deenergization of coil 452 opens the contacts 457 and 454.

The contact 460 which is companion to each unit is allowed to be broken in direct response to the movement of the unit and, therefore, when the units as a group have been started in their forward direction and all contactors 460 have been opened, the holding contact 454 causes the coil 452 to be deenergized. The above arrangement is necessary because of the fact that the valve is actuated from its forward position to feed by a mechanical control dog arrangement, and, if the magnetic actuator is not deenergized prior to such actuation, the valve will again move into a forward approach position.

It should also be clearly understood that each unit is capable of a certain length of approach, which may vary as compared with one of the other units. Therefore, the individual deenergizing of each companion magnetic actuator presents a practical and safe arrangement, and to maintain the relay energized until all of the units have been properly actuated insures that all of the units will be properly started in their forward approach.

As the contacts 458 and 460 are opened, contacts 462 are simultaneously closed, so that when contacts 286 are also closed by valves 214 at the end of the feeding operation, a circuit will be established from the line L-3 through the contactors 442, switches 286, contacts 462, coils 432 and the contactors 442 back to the line L-1. The energization of coils 432 causes the shifting of valves 212 to rapid reverse position as previously discussed. The reverse actuator coils 432 may also be operated at any time after the closing of switches 462 by the "Reverse" control button 463. This control button is adapted to close a circuit through a coil 464 from the line L-3 through the coil 464, switch 463 and main switch 456 back to the line L-1. The energization of coil 464 closes contacts 466 which, if switches 462 are closed, complete a circuit from the line L-3 through contactors 442, switches 466, contacts 462, coils 432 and contactors 442 back to the line L-1. As the head structures are individually restored to home position, control dogs 396 operate controllers 398 to open switches 462 and close switches 458 and 460 slightly before the control dogs 412 shift the valve pistons 212 to a neutral position. It should further be understood that the contacts 462 may be broken manually by manipulating the levers carrying the rollers 402.

From the aforesaid description, it will be apparent that manual control buttons indicated as "Start" and "Reverse" are employed for the purpose of remote control of all of the units and valves provided all of the magnetic controllers 442 are properly in an engaged position. The magnetic actuator 432 is not only used with the reverse button 463 control arrangement, but also is used in conjunction with the individual reversal of each unit in combination with contactor 286. It will further be apparent that the operator is compelled to manipulate either the push button marked "Start," or the push button marked "Reverse" in case any trouble should be experienced, such as improper loading of a work piece or breaking of a cutter or the like. Therefore, if all units 55 are in a forward approach when an emergency arises, the only action had is by manipulating the push button "Reverse" and thereby causing all of the valves to reverse and all of the units to be automatically reversed to their starting positions. 60 The aforesaid control arrangement also allows the remote control to individual units. In other words, I select one of the magnetic controllers 442 through the agency of the proper push button (namely, buttons 444, 446, and 448), and then I 65 use the push buttons "Start" and "Reverse" for manipulating a valve and unit companion to said controller.

Statement of operation

70 Assuming the head frame structures all to be in home or withdrawn position, the operator initiates operation of the machine by first closing the main switch 456 to energize the electrical control circuit. The upper push buttons of the 75 sets of buttons 444, 446 and 448 are then oper-

ated, energizing the motors or prime movers for the individual head frame structures 40a, 40b and 40c. If all the frames are to be operated, all three of the push buttons will be closed. The operation of the push buttons closes the individual magnetic contactors 442, initiating operation of the motors and closing their corresponding conventional motor-holding circuits (not shown). As the motors begin operation, the rapid traverse and feed pumps associated therewith begin the circulation of the hydraulic actuating fluid. At this time the individual control valves 212 are in neutral position, and the valves 214 are also in neutral position so that the fluid delivered by the rapid traverse and feed pumps is merely idly circulated.

The control valves 212 may be manually operated by means of the control levers 436 secured to shafts 252, if desired, but assuming that automatic operation is to be effected, the operator closes the "Start" switch 451. Closing the "Start" switch energizes coil 452 closing contacts 454 and 457. If any of the motors 1, 2 or 3 have been energized, their associated contactors 442 and auxiliary switches 450 will be closed, thereby permitting a holding circuit for the coil 452 to be established through the contacts 454. The closing of the contacts 457 causes the energization of the forward actuator coil 430 for each unit which has been energized. The coils 430 shift the valves 212 to their rapid approach position wherein the ports 234 are aligned with the ports 230 causing the transmission of fluid to the actuators 114 in a rapid approach direction. As the valves 212 are shifted to rapid approach position, the corresponding valves 214 are shifted to feed position by means of the channels 270 as previously described. Accordingly, fluid is also directed from the feed pumps to the actuators 114 to effect the rapid approach movement thereof. As the head structures move away from home position, controllers 398 are operated by control dogs 396 to open switches 458 and 460 and close switches 462 for each unit. This deenergizes the coils 430 and also breaks the holding circuit for the coil 452. As the heads reach their feed position, their associated control dogs 408 cause the mechanical shifting of valves 212 into feed position wherein the ports 234 are aligned with the ports 278. Fluid from the rapid traverse pumps is thus cut off from the actuators 114, but the valves 214 remain in feeding position causing the transmission of fluid from the feed pumps to the actuators and propelling them in the continued forward direction at feeding speed. At the end of the feeding stroke the control dogs 410 operate to shift the valves 212 to neutral position. This causes a shifting of the valves 214 to neutral position by means of the fluid channels 272 and 270 as previously described, but due to the orifice control mechanism 318, Fig. 5, a dwell or delay may be effected in the shifting of the valve members 214. As the valves 214 complete their movements into neutral position, to the right as seen in Fig. 6, switches 286 are operated in the manner previously described. Switches 462 having been previously closed, the closing of switches 286 completes a circuit to the reverse actuating coils 432 causing the shifting of the control valves 212 to rapid reverse position wherein the ports 236 are aligned with the ports 226. Fluid is now circulated from the rapid traverse pumps to the actuators 114 to effect rapid reverse movement. The movement of valves 212 to rapid reverse position does not cause movement of the valves 214 so they remain in neutral

or circulating position. As the head frames return to home or restored position, control dogs 396 cause the opening of switches 462 and the closing of switches 458 and 460. The opening of switches 462 deenergizes the reverse coils 432, but the closing of switches 458 and 460 does not re-energize the forward operating coils 430, due to the fact that switches 457 and 454 have been previously opened and cannot be reclosed except by another operation of the main "Start" button 451. Immediately after the opening of switches 462 as the head frames reach home position, control dogs 412 operate to shift the valves 212 to neutral position. The valves 214 remain in neutral position, and accordingly fluid from both the rapid traverse and feed pumps is again circulated idly within the hydraulic system, and the cycle of operation has been completed. At any time after the head frames have left home position, resulting in the openings of switches 458 and 460, and in the closing of switches 462, the reverse coils 432 may be operated from the "Reverse" button 463 through the switches 466 which are closed by the coil 464 associated with the "Reverse" button. By this means should any emergency or difficulty be encountered, all of the head frame structures may be withdrawn or returned to home position by the manipulation of a single button, the "Reverse" button 463.

It is to be understood, as previously stated, that each head structure is provided with its own control valve 208 and its own control bar 394 and associated control cams and switch structure so that the cycling of the head is controlled in accordance with its own movements after the initiation of the operation by the pressing of the common "Start" button 451.

Valve incorporating reversible feed

In certain instances it is desirable to provide a feed rate in reverse as well as in forward direction. This is accomplished by slightly altering the valve structure 208 previously described, but this altering does not change the structural characteristics, the size of the valve or the control thereof. I have shown this slightly modified valve in Figs. 19 to 21, inclusive, and have designated the valve generally by the numeral 208a. Structures of the valve 208a corresponding with those of the valve 208 are given corresponding numbers. The valve body 254a is made from the same casting as the valve body or housing 254 previously described, it being necessary only to slightly modify the body by machining operations. The valve piston 212a is similar in structure and function with the valve piston 212 previously described, but to effect feed reverse operations the valve piston 214a has been somewhat altered, passageway 276 associated with the passage 270a has been eliminated, the connections to the feed pump have been altered and a stop device 529 has been added for a purpose presently to be described. The dwell orifice device 318 also is eliminated.

More particularly, in this instance the valve 214a is directly connected to the feed pump by means of a conduit 522, the return to the feed pump from the valve being through return conduit 390 as previously described. The conduit 522 communicates with a cross channel 524 provided in valve 214a. This cross channel in turn communicates with a longitudinal channel 526 provided in the valve, the longitudinal channel communicating at its end with another cross channel 528. Cross channel 528 is adapted to communicate with port 266a associated with one

end of the hydraulic actuator, when valve 214a is in the position shown in Figs. 19 and 21, whereas cross channel 524 is adapted to communicate with port 262a connected to the other end of the hydraulic actuator, when valve 214a is shifted to the left. The central portion 527 of valve 214a, is adapted to connect either port 266a or 262a to the return conduit 390 depending upon the shifted position of the valve.

The stop mechanism for the valve 214a comprises a cam 530 secured to the control shaft 252 of the valve 212a, the cam being secured on the shaft by means of a pin 542. This control cam is adapted to actuate the stop pin or abutment member 529 through the intermediary of a ball 538. To this end the ball is adapted to engage in a slot 540 in the abutment pin, the arrangement being such that when the ball is thrust to the right, as seen in Fig. 21, by the cam, the stop pin 529 will be raised. A spring 534 adjustably held in position by means of a threaded member 536 serves normally to hold the stop pin downwardly in stopping position. It will be noted from Figs. 19 and 21, that the electrical contactor piston 294 associated with switch 286 has been machined as indicated at 542 so as to enter a counter-bore 544 in valve 214a.

In the operation of the feed reverse valve structure, and assuming the valve pistons 212a and 214a to be in their neutral positions, the valve piston 212a is first shifted either manually or by manipulation of the "Start" switch 451 to its rapid approach position alining port 234a with the port 230a, causing the transmission of fluid to the hydraulic actuator in rapid approach direction as previously described. As the valve 212a is shifted, fluid is transmitted through passages 278a and 270a shifting the valve member 214a to its extreme left position which is its feed approach position wherein cross channel 524 is alined with port 262a and port 266a is connected to the return conduit 390. Accordingly fluid is also directed from the feed pump to the hydraulic actuator by means of the valve 214a. As the head structure associated with the valve reaches a predetermined position, a control dog operates to shift valve 212a to its feed approach position wherein port 230a is cut off from port 234a but pressure fluid communication is maintained between port 234a and passage 278a to hold valve 214a in its feed approach position. Accordingly communication between the rapid traverse pump and the hydraulic actuator is cut off, but communication between the feed pump and the actuator is maintained and the actuator progresses at feeding speed.

At the end of the forward feed operation a control dog shifts valve 212a to its feed reverse position wherein the port 236a of the valve is alined with channel 282a causing the hydraulic shifting of valve piston 214a to the right, into the position shown in Figs. 19 and 21, wherein the valve piston engages the stop pin 529 which is at this time in operative position. This position of valve 214a is its feed reverse position, wherein the cross channel 528 is connected to port 266a, the port 262a being connected to the return conduit 390. Accordingly in this position of the valves fluid is transmitted from the feed pump to the hydraulic actuator to effect a feed reverse movement, communication between the actuator and the rapid traverse pump being cut off.

At a predetermined position in the movement of the head structure a control dog further operates valve 212a to its neutral position wherein

the stop pin 529 is raised by the correlated movement of shaft 252. In the neutral position of valve 212a channel 282a remains in pressure communication with port 236a, thus causing valve 214a to complete its movement to the extreme right, to its neutral position. As valve 214a reaches its neutral position, switch 286 is operated, and the operation of this switch causes the operation of the reverse actuating coil to shift the valve 212a to its rapid reverse position, as previously described, wherein the port 236a is alined with the port 226a, while leaving channel 282a in communication with port 236a so as to maintain the valve 214a in its neutral position. In the neutral position of valve 214a the valve is shifted sufficiently to the right so as to bypass inlet conduit 522 directly to the exhaust port 390 by means of valve passage 527. Accordingly the feed pump is operatively disconnected from the hydraulic actuator, but the rapid traverse pump is now connected with the hydraulic actuator so as to effect the rapid reverse movement thereof. As the head frame reaches home position, a dog shifts valve 212a to neutral position cutting off communication between ports 236a and 226a, thus cutting off communication between the rapid traverse pump and the hydraulic actuator, but leaving port 236a in communication with channel 282a to maintain the valve 214a in its neutral position. Both the rapid traverse and the feed pumps are now cut off from communication with the actuator and the cycle of operation is complete.

Attention is also directed to the disclosure of a modified electrical actuator designated generally by the numeral 422a in Fig. 13. This actuator is a modification of the actuator 422 shown in Fig. 11, and is adapted to be connected directly with one extremity of the valve member 212, as distinguished from the inter-connection made with said valve by the magnetic actuator 422.

Obviously numerous modifications and changes may be made without departing from the spirit and scope of the above described invention.

45 The invention is hereby claimed as follows:

1. Valve mechanism including a valve housing, a shiftable valve member in said housing, said housing and valve member having cooperative passages for directing fluid to an actuator to be controlled thereby, a second valve member adapted to be shifted by fluid directed thereto by said first valve member, said second valve member having passages for directing fluid to an actuator to be controlled, means for supporting an electrical contactor in position to be acted upon by said second valve member, and means operated by the electrical contactor in predetermined timed relation with the shifting of said second valve member.

60 2. Valve mechanism including a valve housing, a shiftable valve member in said housing, a second valve member in said housing adapted to be shifted by fluid directed thereto by said first valve member, said second valve member having passages for directing fluid to a fluid operated actuator structure, means in said housing for supporting an electrical contactor in position to be acted upon by said second valve member, and means operated by the electrical contactor for operating the first valve member, said valve members and housing having cooperative fluid conducting adjustable valve controlled passages whereby to cause a movement of said second valve member at various speeds.

75 3. Valve mechanism including a valve housing,

a shiftable valve member in said housing, said housing and valve member having cooperative passages for directing fluid to an actuator to be controlled thereby, a shiftable piston member, means including a fluid passage controlled by the valve member having an adjustable metering orifice therein for controlling the shifting of the piston member, means for supporting an electrical contactor in a position to be acted upon by said piston member, and means operated by the electrical contactor in predetermined timed relation with the shifting of said piston member.

4. Valve mechanism including a valve housing, a shiftable valve member in said housing, said housing and valve member having cooperative passages for directing fluid to an actuator to be controlled thereby, a second valve member having fluid actuated means adapted to be shifted by fluid controlled by said first valve member, said second valve member having passages for directing fluid to an actuator to be controlled, and means operated by the shifting of the second valve member for operating the first valve member.

5. Valve mechanism including a valve housing, a shiftable valve member in said housing, said housing and valve member having cooperative passages for directing fluid to an actuator to be controlled thereby, a piston member shiftable in the housing, fluid conduits in the housing between the valve and opposite ends of the piston member whereby the piston member is adapted to be shifted selectively in opposite directions by fluid directed selectively to opposite ends of the piston from the valve member, restricted orifice means arranged in the fluid conduits to control the speed of operation of the piston member in at least one direction, and means operated by the shifting of the piston member for operating the valve member.

6. In a power control unit, a structure for controlling the transmission of power from a power source to a power operated mechanism, said structure comprising a first shiftable power transmission control member for effecting the operation and control of an operated device, a second shiftable power transmission control member for effecting the independent operation of said operated device, means for effecting the shifting of the second control member by the first control member, means for effecting the shifting of the first control member by the second control member, and means for adjustably controlling the time of response of said second control member to operation of the first control member.

7. Valve mechanism including a valve housing, a shiftable valve member in said housing, said valve member having means for effecting the selective control of a fluid operated actuator, said valve member being shiftable from an operative actuator controlling position to an inoperative position wherein fluid is circulated through a conduit in the body of the valve member, a restricted orifice arranged in said conduit, and means for adjusting said orifice whereby to provide for a predetermined pressure drop of fluid passing through the orifice.

8. Valve mechanism including a valve housing, a shiftable valve member in said housing, a fluid receiving port in the housing, a pair of fluid channels in the valve member adapted to be brought selectively into operative association with said fluid receiving port by the shifting of the valve member, a fluid discharge port in the housing adapted to receive fluid from one of the

valve member channels in a predetermined shifted position of the valve member, said valve member having means for effecting the selective control of a fluid operated actuator, and a restricted orifice means arranged in the other of said valve member channels, and means for adjusting said orifice means whereby to provide for a predetermined pressure drop of fluid passing through the orifice.

10. 9. In a fluid control mechanism, a housing, a cylindrical valve member shiftable in said housing, a fluid receiving port in the housing, a channel in the valve member adapted to be brought into cooperation with the housing port by the shifting of the valve to receive fluid therefrom, said channel extending radially inwardly from the cylindrical surface of the valve and then in opposite directions to the valve end faces, and fluid flow restriction means arranged in said valve member channel adapted by the flow of fluid therethrough to maintain a control fluid pressure within said fluid receiving port.

10. In a fluid control mechanism, a housing, a valve member shiftable in said housing, a fluid receiving port in the housing, a channel in the valve member through which fluid is continuously circulated when the channel is brought into cooperation with the housing port by the shifting of the valve to receive fluid therefrom, fluid flow restriction means arranged in said valve member channel adapted by the flow of fluid therethrough to maintain a control fluid pressure within said fluid receiving port, and means including a second shiftable valve operatively associated with said port and adapted to be shifted by the pressure fluid therein.

11. Valve mechanism including a valve housing, a shiftable valve member in said housing, said valve member having passages for selectively directing fluid to a fluid operated actuator structure, passages in the housing through which fluid may be propelled to effect the hydraulic shifting of the valve member, orifice means in the passages for controlling the speed of operation of the valve member, electrical means operable in response to the shifting of the valve member, and means controlled by the electrical means for shifting said valve member.

12. Valve mechanism including a valve housing, a shiftable valve member in said housing, passages for fluid in the housing through which fluid may be propelled to effect the hydraulic shifting of the valve member, restricted orifice means in said passages to control the speed of operation of the valve member, means for rendering the orifice means effective during an initial movement of the valve member and ineffective during a subsequent movement thereof, an electrical contactor operated by the subsequent movement of the valve member, and means controlled by the electrical contactor for shifting the valve member.

13. In a hydraulic and electrical power control structure, a hydraulic power control device, said device comprising means arranged to control a fluid power circuit having a fluid operated actuator, means arranged to control an electrical power circuit, and means operatively connecting the electrical control means and the fluid power control means for effecting the actuation of the electrical control means by operation of said fluid power control means, said connecting means including an adjustable restricted orifice and an unrestricted orifice arranged in by-pass relation to the restricted orifice for controlling the time

of operation of the electrical control means in response to the operation of the fluid control means, and means controlled by the electrical control means for controlling the operation of the fluid power control means.

14. Valve mechanism including a valve housing, a shiftable valve member in said housing, said housing and valve member having cooperative passages for directing fluid to a fluid actuator to be controlled thereby, a second valve member having fluid actuated means adapted to be shifted by fluid controlled by said first valve member, said second valve member having passages for directing fluid to a fluid actuator to be controlled, and electrical means operated by the shifting of the second valve member for operating one of said valve members.

15. Valve mechanism including a valve housing, a shiftable valve member in said housing, said housing and valve member having cooperative passages for circulating fluid when the valve member is in one position and for directing fluid to a fluid actuator to be controlled thereby when the valve member is in another position, a shiftable second valve member arranged to circulate fluid when in one position and to transmit fluid to a fluid actuator when in another position, and adapted to be shifted by said first valve member by fluid directed thereto, means including a restricted fluid control orifice for controlling the speed of shifting of said second valve member, an electric switch operated by the shifting of the second valve member, a solenoid controlled by the switch, and means operated by the solenoid for operating said first valve member.

16. Valve mechanism including a valve housing, a shiftable valve member in said housing, said valve and housing having cooperative passages for controlling the transmission of fluid to a fluid actuator, a shiftable piston member in said housing, fluid conduits connecting said valve member and opposite ends of the piston member whereby the piston member is adapted to be shifted selectively in opposite directions by fluid directed thereto by said valve member, a control orifice for controlling the speed of movement of the piston member in at least one direction, a relatively unrestricted fluid passage in bypass relation to said orifice for rendering it ineffective, an electrical contactor adapted to be operated by the piston member, and means operated by the electrical contactor for operating the valve member.

17. Valve mechanism including a valve housing, a longitudinally shiftable valve member in said housing having a plurality of operative positions for effecting the selective operation of a fluid operated device, a second valve member longitudinally shiftable in said housing adapted to be moved to a plurality of operative positions for effecting the selective operation of a fluid operated device, passages within the housing connecting the valve members whereby movement of the first valve member to a given position effects the hydraulic shifting of the second valve member

to a predetermined position, an electric switch operated by the second valve member, and a solenoid for operating the first valve member operated by said switch.

18. Control mechanism comprising a first shiftable valve member adapted to be associated with a fluid power circuit, a second shiftable valve member adapted to be associated with a fluid power circuit, said first valve member having a circulating position and a plurality of operative positions wherein it reversibly directs the flow of fluid within its associated fluid power circuit and wherein it reversibly controls the shifting of the second valve member, said second valve member having a circulating position and an operating position wherein it directs the flow of fluid within its associated fluid power circuit, and means associated with the second valve member for effecting a shifting of the first valve member by the shifting of said second valve member.

19. Control mechanism comprising a first shiftable valve member adapted to be associated with a fluid power circuit, a second shiftable valve member adapted to be associated with a fluid power circuit, said first valve member having a circulating position and a plurality of operative positions wherein it reversibly directs the flow of fluid within its associated fluid power circuit and wherein it reversibly controls the shifting of the second valve member, and said second valve member having a circulating position and a plurality of operative positions wherein it reversibly directs the flow of fluid within its associated fluid power circuit.

20. Control mechanism comprising a first shiftable valve member adapted to be associated with a fluid power circuit, a second shiftable valve member adapted to be associated with a fluid power circuit, said first valve member having a circulating position and a plurality of operative positions wherein it reversibly directs the flow of fluid within its associated fluid power circuit and wherein it reversibly controls the shifting of the second valve member, and said second valve member having a circulating position and a plurality of operative positions wherein it reversibly directs the flow of fluid within its associated fluid power circuit, and means associated with the second valve member for effecting the shifting of the first valve member by the shifting of said second valve member.

21. Control mechanism comprising a first valve member, a second valve member, hydraulic operating means for the second valve member controlled by the first valve member, a stop member for preventing a predetermined operation of the second valve member by the hydraulic means when said stop member is in operative position, said stop member being associated with the first valve member and operable thereby, and an electric switch arranged to be operated by the second valve member upon operation thereof on release of the stop member.
